UNITED STATES PATENT OFFICE.

CHARLES T. MARTON, OF ROCHESTER, NEW YORK.

TRAFFIC SIGNAL.

Application filed August 19, 1925. Serial No. 51,259.

The present invention relates to traffic signals for highways and has for one object to provide an improved signal in the nature of an illuminated standard or sign post which will afford a maximum amount of light at a minimum cost and one which will stand out prominently and illuminate a relatively large area of that portion of the street or highway immediately surrounding the signal.

A further object of the invention is to provide a signal of the character described comprising improved illuminating and reflecting means embodying a simple construction which can be economically manufactured and maintained and which will be both durable and efficient in service.

To these and other ends the invention resides in certain improvements and combinations of parts, all as will be hereinafter more fully described, the novel features being pointed out in the claims at the end of the specification.

In the drawings:

Figure 1 is a side elevation illustrating one embodiment of the invention;

Figure 2 is a sectional elevation on an enlarged scale taken centrally through the signal shown in Figure 1;

Figure 3 is a top plan view of the signal;

Figure 4 is a plan view looking downwardly as indicated by line 4^a—4^a in Figure 2, the cap being removed;

Figure 5 is a sectional plan taken on line 5^a—5^a of Figure 2, and

Figure 6 is a sectional plan taken on line 6^a—6^a of Figure 2.

Similar reference numerals throughout the several views indicate the same parts.

The traffic signal illustrated in the drawings is preferably intended to occupy a central position in a street or highway or at the center of intersection of two streets or highways and is not only provided with indicia or markings by which both vehicular and pedestrian traffic may be warned but is so designed as to afford a high degree of illumination to permit the signal to be more readily seen from a distance whereby it will stand out as an unfailing precautionary means affording ample warning for traffic approaching from all directions. The indicia or markings may constitute any desired note of warning, such as that indicated in Figure 1, being preferably what may be termed a "stop" signal on the two sides of

the column or standard which can be seen by those approaching a main highway from a cross street, the opposite sides preferably containing merely a suitable slogan of safety in cases where the main highway traffic is given the right of way over that of its intersecting streets. However, if desired the same indicia may be applied to all sides of the signal.

In addition to serving as a safety and street illuminating signal, the column or standard is provided with panels displaying the names of the streets at the intersection at which the signal is placed and is also provided on all four sides with the usual red lights as additional precautionary means.

Referring to the drawings, 10 represents a base or support for a column or standard indicated generally at 11, the base having a contour preferably as outlined in Figure 3, and comprising a suitable form of construction, such as a metal container, filled with a suitable material, such as concrete, as indicated at 12 in Figure 2. The top 13 of the container is flanged upwardly at 14 to engage the inwardly turned flange 15 of a hollow casing member 16 which is flanged inwardly at its upper end to form a horizontally disposed ledge or shoulder 17 terminating in an upstanding flange 18 as shown in Figure 2. The hollow member 16 is constructed to form a base for the column proper which is preferably beveled at its corners and provided with outwardly projecting disk shaped portions 19 to afford a certain degree of ornamentation as well as to stiffen the sides of said hollow base member.

The column or standard includes four upstanding frame members or posts, each preferably comprising inner and outer sections 20 and 21, respectively, both of which are channel or trough shaped, the outer section preferably having its vertically disposed edges bent around the corresponding edges of the inner section, as shown in Figure 5. These corner members have their lower ends disposed upon the inwardly turned flange portions 17 of the hollow casing 16, as shown in Figure 2, and at their upper ends are adapted to receive a suitable cap or cover 22 of any desired shape. Immediately beneath the cap the corner members are connected by the metal panels 23, preferably by welding, said panels forming tie plates between the corner posts and serving also as holding means for the translucent lens ele-

ments 24, preferably comprising the usual red stained glass signals disposed in openings formed in said tie plates and supported by suitable clips or holders 25. The cap 22 is connected to the plates 23 by means of screws 26 as shown in Figure 2. Additional tie members 27 are disposed between the corner posts below the tie members 23, having their ends connected with said posts in any suitable manner, preferably by welding.

Transparent or translucent panels 28 are disposed between the upper and lower tie plates 23 and 27, the same being secured by suitable brackets or holders 29, as shown in Figure 2. The panels 28 are preferably provided for displaying the names of streets or highways as indicated in Figure 1, but may be provided with other indicia or markings of any nature desired.

Between the base member 16 and the tie plates 27 are provided relatively long and narrow upright panels 30 preferably formed of transparent material, such as glass, but which may be constructed of translucent or other material if desired. The lower ends of the panels 30 are adapted to rest upon the shoulders or flange portions 17 of the base member 16, while their upper ends rest against the inner faces of the tie plates 27. The panels 30 are preferably clamped against the inner faces of the corner posts by means of suitable clips or brackets 31 as shown in Figure 5.

The structure above described constitutes a hollow standard or column in which the mirrors, reflectors and lamps are disposed and by which the legends or markings of the panels 28 and 30 are made clear, the desired amount of illumination being afforded for rendering the illuminated signal visible for a comparatively long distance.

Disposed within the column opposite the panels 30 and extending longitudinally therein is a reflector or reflecting device, indicated generally at 32 and including separate reflecting surfaces for each of the panels 30. These reflectors are preferably constructed of two trough-shaped members 33 between which are disposed the plates 34, each of which constitutes a portion of one reflector. The members 33 and 34 are preferably secured together, as by welding, to form a complete unit which can be inserted within the column before the cap 22 is applied thereto. The edges of the trough-shaped members are disposed between the brackets or clips 31 which hold the panels 30 in position, as shown in Figure 5. Preferably the intermediate reflecting surface of each reflector is inclined, from a point adjacent its center, away from the panel 30 as shown in Figure 2, whereby to project the rays of light at an angle inclined to the axis of the column for the purpose of throwing the light upwardly and downwardly to more

effectively illuminate the area surrounding the signal. The angularly disposed metallic surfaces of each reflector may be enameled or otherwise coated with suitable material adapted to provide a high degree of refraction, or if preferred the reflectors may be in the form of mirrors or highly polished metal surfaces.

Located within the hollow standard above and below the reflectors are suitable illuminating elements, such as the electric lamps 35 and 36, the light of which is reflected downwardly and upwardly, respectively, by the upper and lower mirrors 37 and 38, so that all of the reflecting surfaces are highly illuminated by the light projected through the open ends of the reflecting device. The mirrors are preferably inclined as shown to better project the light into the openings or passages between the panels 30 and the reflectors lying opposite the same. The lower mirror 38 is supported by a suitable frame or holder 39, having its peripheral edge bent over the edge of the upstanding flange 18 of the base member 16 and secured by suitable clips 40 as shown in Figure 2. The lamp 36 is projected through an opening 41 in the mirror 39, slightly into the central opening 42 of the reflector 32, which is large enough to accommodate the lamp and permit it to pass therein when unscrewed from its socket 43. A plate 44 covers the opening in the mirror through which the lamp is projected and prevents the loss or escape of light downwardly through the mirror. The mirror 38 and its frame preferably constitute a unit which may be removed as such from the column. To permit of the removal of said mirror and other parts contained in the column one of the panels 30 is preferably hinged upon the column by suitable means not shown.

The upper mirror 37 is also carried by a suitable frame, indicated at 45, and having downwardly extending portions 46 adapted to project into and be supported by the yoke-shaped brackets 47, shown in Figures 2 and 4, the mirror sections being held within the frame by suitable clips 48 supported by brackets 49 on the frame 45.

The lamp 35 is screwed into a socket 50 carried by a strap 51 having its end portions removably projected into the brackets 47 and resting upon the frame 45 of the mirror. The lamp 35 may be unscrewed and removed through the side of the column provided with the hinged panel mentioned above. Upon removal of the cap 22 the mirror 37 and yoke 51 may be removed through the top of the column.

The socket 43 of the lamp 36 is carried by a yoke-shaped member 52 secured to a plate 53 having an opening 54 therein for the passage of the electric wires, not shown, for supplying current to the lamps, the

wires for both lamps being preferably carried upwardly through an opening 55 in the filler 12 of the base 10.

Means for anchoring the column upon the top of the base 10 comprises a plurality of arms or straps 56 having their upper ends secured to the inner faces of the corner posts, as by welding, and their lower ends provided with inwardly turned portions 57 for the reception of the bolts 58, the heads of which are anchored in the concrete base 12 as shown in Figure 2. The lamp carrying plate 53 is adapted to rest upon and be supported by the inwardly turned portions 57 of the straps and also serves to brace and tie the lower ends of the members 56 together. By tightening the nuts of the bolts 58 before the mirror 38 is inserted within the column the corner posts and the structure carried thereby may be clamped upon the base member 16 and the latter upon the top 13 of the main base 10 as shown in Figure 2.

With the invention illustrated and described herein, it will be seen that a maximum amount of illumination is afforded with a minimum number of lamps because of the particular arrangement of lamps, mirrors and reflectors shown. Furthermore, the construction is such that should either light become extinguished the other will be sufficient to afford a fair degree of illumination.

I claim as my invention:

1. A highway signal comprising a hollow standard having indicia holding panels at its sides, a longitudinally extending reflector disposed between said panels and having reflecting compartments, open at one end, illuminating means adjacent said end of the reflector, and means adapted to project the light of said illuminating means through said end and between the reflector and said panels whereby to illuminate the latter.

2. A highway signal comprising a hollow standard having vertically disposed indicia holding panels at its sides, a longitudinally disposed reflector open at one end and projecting between said panels and having separate reflecting compartments, illuminating means adjacent said open end of the reflector, and a mirror including portions inclined with respect to the axis of the standard adapted to project the light of said illuminating means through said open end and into said compartments, whereby to illuminate said panels.

3. A highway signal comprising a hollow standard having indicia holding panels at its sides, a reflector extending longitudinally between said panels for reflecting light thereto, a series of translucent elements opposite one end of said reflector, a lamp within said standard adapted to both illuminate said translucent elements and said re-

flector, and means for projecting the light of the lamp upon said reflector.

4. A highway signal comprising a hollow standard having indicia holding panels at its sides, a reflector extending longitudinally between said panels in spaced relation thereto having a reflecting surface for each of the panels, a mirror within the standard, opposite one end of the reflector, a series of translucent elements between the mirror and said reflector, and illuminating means disposed between the mirror and said reflector end adapted to both illuminate said translucent elements and said reflector.

5. A highway signal comprising a hollow vertical standard having indicia holding panels, a light source within one end of the standard, a member having reflecting surfaces extending longitudinally within the standard in spaced relation to said panels for reflecting light thereto, said reflecting surfaces being inclined to the axis of the standard, and a mirror adapted to project light from said surfaces.

6. A highway signal comprising a hollow standard having indicia holding panels at its sides, a unitary device insertible longitudinally within the standard and embodying a series of separate compartments opposite said panels open at their ends, the walls of said compartments forming light reflecting surfaces, illuminating means located within the standard and outside of said compartments, and means for reflecting the light of said illuminating means into said compartments through the open ends thereof.

7. A highway signal comprising a hollow standard including a plurality of vertically disposed corner members, transparent panels disposed vertically between said corner members, spaced guides secured upon the inner faces of each of said corner members, upstanding trough-shaped reflectors within the standard disposed opposite said panel and having their edges projecting between said guides, illuminating means within the standard and means for projecting the light of said illuminating means into said trough-shaped reflectors.

8. A highway signal comprising a hollow base, upstanding frame members carried by said base, vertically disposed indicia holding panels extending between said frame members and forming therewith a casing, a cover upon the upper end of said casing, reflectors spaced from and projecting vertically within the casing opposite each of said panels and means mounted within the standard independently of the reflectors and outside thereof for illuminating the space between each panel and its reflector.

9. In combination a support, a standard including a hollow base mounted upon the support having upstanding frame members and transparent panels disposed between

- said frame members, means within the standard for illuminating said panels, securing members projecting downwardly within the base from said frame members, connecting means between said securing members and said support adapted to permit the standard to be clamped upon the support, and a holder for the illuminating means carried by said securing members.
10. A highway signal comprising a hollow standard having a plurality of side panels, a reflector open at one end and extending longitudinally between said panels and having compartments with reflecting surfaces opposite the panels, and illuminating means for the reflector disposed within the standard opposite the open end of the reflector through which light is directed to said reflecting surfaces to illuminate the panels.
15. A highway signal comprising a hollow standard having vertically disposed transparent panels at its sides, a longitudinally extending reflector open at one end and disposed between said panels including angularly disposed reflecting surfaces forming separate compartments arranged opposite the panels, illuminating means adjacent one end of said member located outside of the compartments, and means adapted to project 20 the light from said illuminating means into said compartments and upon said angularly disposed reflecting surfaces.
25. A highway signal comprising a hollow standard having vertically disposed transparent panels, an open ended reflector having a series of compartments extending longitudinally within said standard between said panels, each compartment having a plurality of reflecting surfaces disposed opposite each panel, illuminating means adjacent the opposite ends of said reflector, and means 30 for projecting the light of said illuminating

means through the ends of the reflector upon the several surfaces thereof.

13. A highway signal comprising a vertically disposed hollow standard having indicia holding panels at its side, a light source, and a unitary reflector insertible longitudinally within the standard embodying separate compartments each open at one end, one wall of each of the compartments being adapted to reflect the light upon said panels, the light source being disposed within the standard opposite the open end of said compartments. 45

14. A highway signal comprising a hollow standard including a plurality of vertically disposed corner members having guideways formed thereon, transparent panels disposed vertically between said corner members, upstanding trough-shaped reflectors extending longitudinally within the standard and terminating short of the upper end thereof and being disposed opposite said panels and having their outer vertical edges terminating within said guideways, and means for illuminating the space between said panels and reflectors, said means being disposed within the standard above said reflectors. 60

15. In a highway signal, a base, a hollow standard projecting upwardly therefrom and having a plurality of indicia holding panels, a reflecting device extending vertically within the standard terminating short of the ends thereof and embodying a plurality of separate compartments open at their ends, the walls of said compartments forming reflectors for projecting light rays on said panels, a lamp opposite each end of 75 said reflecting device and means arranged to project light into the several compartments. 80

CHARLES T. MARTON.
